UNITED STATES PATENT OFFICE.

SAMUEL E. DIESCHER, OF WILKINSBURG, PENNSYLVANIA, ASSIGNOR TO S. DIESCHER & SONS, OF PITTSBURGH, PENNSYLVANIA, A CORPORATION OF PENNSYLVANIA.

MILL FOR PIERCING BILLETS.

Application filed August 27, 1923. Serial No. 659,425.

A form of apparatus for piercing ingots or billets consists of rolls arranged in such relation that planes coincident with their axes will intersect at an acute angle, said 5 rolls being rotated in the same directions. Rolls so arranged will act most effectively if the work-piece is so supported that the axis of the work-piece and a line connecting points on the rolls most closely adjacent, 10 will be in the same plane. When the work-piece is in such position, the forces to which it is subjected (the weights of the work-piece and mandrel being disregarded) are equally effective to move the work-piece up 15 or down, and a small movement of the work-piece from such position will bring about an unbalancing of such forces and the billet will be further shifted. Such shifting of the work-piece may be prevented 20 by the employment of guides arranged above and below the path of longitudinal movement of the work-piece. Such guides would bear on the work-piece for considerable distance on each side of the zone of action 25 of the rolls, and as the work-piece moves along and also transversely of the guides, the latter would be quickly rendered ineffective by reason of wear and excessive heating. And further, such oppositely disposed 30 guides are objectionable for the reason that, due to lack of homogeneity of the steel, and the difficulty in obtaining absolutely uniform temperature at all points on the work-piece, e. g., hard and soft spots, the work- 35 piece is more or less bulged out or enlarged at points along the pierced portions and hence the work-piece might become stuck between the guides.

In order to overcome the foregoing and 40 other difficulties encountered, it is the present practice to so mount the rolls that the distance between the most closely adjacent portions of their working faces will be less than the diameter of the work-piece, and the 45 work-piece is so fed between the rolls that its axis is above a horizontal plane passing through the intersection of planes coincident with the axes of the rolls, so that the rolls will exert oppositely acting pressures on 50 opposite sides of the work-piece at points below a longitudinal plane passing through the axis of the work-piece. The tendency of such pressure is to force the billet upwardly and hence a guide must be employed to hold the work-piece in operative position. 55 It is the usual practice to construct these guides in the form of rollers freely rotating on an axis parallel or approximately parallel with the axis of the work-piece. The roller so mounted presents little resistance to the rotation of the work-piece but a very considerable resistance to the longitudinal movement of the work-piece. The roller is made of such a length and is so supported as to bear on the work-piece 60 for a considerable distance on both sides of a vertical plane passing through the points of contact of the rolls with the work-piece, and hence when a bulge or enlargement 65 formed on the work-piece in the piercing 70 operation, comes in contact with the guide roller, and if the bulge or enlargement is considerable, the work-piece will be bent and forced down on the mandrel subjecting the latter to injurious transverse strains, 75 and militating against the piercing action.

As is well understood by those skilled in the art, the effectiveness of the lateral pressure on the work-piece to force it upward, increases with the distance of the path of the work-piece above the horizontal plane passing through the intersection of planes coincident with the axes of the rolls, and that the reducing efficiency of the rolls increases as the axis of the work-piece is 85 brought nearer said plane. But as the line of feed approaches such plane the lifting component of the lateral pressures of the rolls on the work-piece becomes less effective to prevent the dropping down of the 90 work-piece by reason of the weight of the work-piece and mandrel. Hence it is the present practice to so adjust the rolls for a given diameter of billet in such proximity one to the other, that the lifting component 95 of the pressure of the rolls on the work-piece will be in excess of the weight of the work-piece and mandrel and to employ a guide roller to hold the work-piece in position to be acted on by the rolls, as herein-after stated.

The necessity of adjusting the relative positions of the rolls in accordance with the diameter of the work-piece, rendered it practically impossible to pierce a small work-piece. The adjustment of the rolls into close proximity so reduces the V-shaped space between the rolls in which the guide roller 105

- must be arranged, that a roller having sufficiently large diameter to sustain the transverse strains to which it must be subjected, cannot be placed in operative position.
- 5 When the rolls are so adjusted that the line of feed of the work-piece must be outside of the line connecting the nearest points on the peripheries of the rolls, the employment of a guide extending along the work-
- 10 piece on both sides of the point of reduction necessitates the feeding of the work-piece above such line and the guide above the work-piece, as if the billet were fed below such line, such guide would be below the
- 15 billet and in the path of scale dropping from the work-piece.

The invention described herein has for its object the provision of a guide for the work-piece in a piercing mill which will obviate difficulties encountered in the present practice and will greatly facilitate the piercing operation. The invention is hereinafter more fully described and claimed.

In the accompanying drawings forming a part of this specification, Fig. 1 is a diagrammatic elevation showing the relative positions of the reducing rolls and guide roller in a mill embodying the invention described and claimed herein; Fig. 2 is a side elevation of the same; and portions of the billet and guide roller being shown in section; and Fig. 3 is a sectional plan view.

In the practice of the invention the reducing rolls 1 are constructed and mounted in a suitable manner with their axes *a* and *b* arranged at an angle the one to the other according to rules known in the art, and are adapted to be rotated by any suitable construction of driving mechanism in the same direction. The faces of the rolls operative on the billet are curved transversely or substantially so. In order to avoid the employment of two guides or members to maintain the work-piece in position to be pierced, as would be necessary if it were so passed between the rolls that its axis would be in a horizontal plane *c* coincident with the intersection of planes coincident with the axes of the rolls, the latter are adjusted in such relation that the distance between points on the operative faces of the rolls lying in said horizontal plane will be sufficiently less than the diameter of the work-piece at the place acted on by the reducing rolls, to prevent the passage of the work-piece laterally between the rolls. With rolls so adjusted, the line of feed of the work-piece will be at one side (above or below the plane indicated by the line *c*) and provision is made for preventing the vertical displacement of the work-piece by the lateral pressure of the rolls. In lieu of employing a guide roller with its axis parallel with the line of feed of the work-piece, the invention claimed herein contemplates the employment of a disc 2 having

its axis of rotation at right angles to the path of movement of the work-piece. This disc is secured on a shaft 3 mounted in bearings 4 so arranged that scale dislodged from the work-piece will not lodge on the bearings. This guide is preferably driven as hereinafter described. This guide disc or roll is so arranged as shown in Fig. 2 that its axis of rotation will be in or approximately in a vertical plane *d* bisecting the work-piece at the point of maximum reduction by the rolls, and hence that component of the lateral pressure of the rolls tending to move the work-piece vertically, will be directly opposed by the guide roll.

Although the pierced portion of a work-piece will have an external diameter at least equal to the unpierced portion, the rolls effect a substantial reduction of the diameter of the portion being operated on, and hence the guide roll or disc heretofore employed do not bear on the portion of the work-piece being acted on by the reducing rolls. And further, it is the practice in some cases to pierce an ingot as it comes from the mold, and as such ingot is necessarily tapered from one end to the other only the ends of the guide roller now used will bear on the ingot and due to the successive increments of feed of the ingots having gradually varying cross-sectional dimensions, the axes of the work-piece and mandrel, respectively, will not coincide and will therefore bring about a condition of strain on both the ingot and the mechanisms. In the employment of the improvement described and shown herein the guide roll or disc 2 which is preferably made with a grooved periphery, has its periphery at the root of said groove corresponding substantially to the transverse curvature of the peripheries of the reducing rolls so that it will conform to the surfaces of the portion of the work-piece being acted on by the reducing rolls. It will be understood that when reference is hereinafter made to the radius or diameter of the guide roll or disc, the shortest radius or diameter of said roll or disc is meant.

As hereinafter stated, the presence of hard and soft spots in the billet, due to unequal heating or other causes, will cause a bulging or enlargement of the periphery of the work-piece, but as such bulging or enlargement cannot occur except after the surface of the work-piece has passed out of contact with the reducing rolls, they cannot have any effect when employing the character of guide roll or disc claimed herein, when the transversely curved faces of the reducing rolls have radii equal to the radii of the perimeter of the guide roll, as is the preferred construction, as when said parts are so constructed and relatively arranged as hereinbefore stated, the contact of the reducing rolls and guide disc on the work-

piece along the billet are substantially the same.

While being operated on by the rolls of a piercing mill, a helical movement is imparted to the work-piece, i. e., it is moved longitudinally and also rotated. It has been the general practice to provide a stationary guide to support the work-piece in operative relation to the reducing rolls and 10 the guide was worn away due to the two movements of the work-piece on the guide. In some cases a roller was used in place of the solid guide, its axis of rotation being parallel with the axis of the work-piece, but 15 as the direction of rotation of such rollers was at an angle to its longitudinal movement there would not be any reduction of friction opposing the longitudinal movement of the work-piece. Such a guide roll 20 is cylindrical in form and does not support the work-piece at that portion undergoing reduction by the main rolls of the piercing machine.

In the construction shown and described 25 herein the guide roll or disc can be rotated so that its peripheral speed is equivalent to the rate of longitudinal movement of the work-piece, but in such case the frictional resistance due to the angular movement of 30 the surface of the work-piece relative to the movement of the surface of the guide roll or disc would be substantially the same as if a stationary guide were used. On the other hand the guide roll or disc can be so 35 rotated that the friction between the guide roll or disc and the work-piece due to the rotation of the latter, can be reduced and if desired wholly eliminated. In this case the relative circumferential speed of rotation 40 of the work-piece and the rotation of the guide roll or disc would be such that the speed of the guide roll is greater than the circumferential speed of the work-piece. Any speed of the guide roll and disc greater 45 than the longitudinal speed of travel of the work-piece tends to cut down friction against rotation of the work-piece. Also any speed of the surface of the guide roll or disc at a higher rate of movement than 50 that of the longitudinal movement of the work-piece between the reducing rolls would tend to draw the work-piece along.

These functions can be attained by rotating the guide rolls at a speed so related 55 to the speed of rotation of the work-piece that the peripheral speed of the guide roll is approximately one-half the peripheral speed of the work-piece divided by the sine of the average angle of the helix of feed of 60 the work piece through the pass.

When the relationship of speed between reducing rolls and the guide roll or disc is such as set up in the above formula, then 65 the friction between the work-piece and the guide has been totally eliminated or

there are neither circumferential nor longitudinal frictions incurred by the work-piece mitigating against its passage through the mill. However, it would be understood that this entire matter is one of diverting 70 the friction between the work-piece and the guide roll into a useful effect instead of a detrimental one. That friction which ordinarily occurs against rotation and longitudinal travel of the work-piece, is by this 75 method wholly confined to longitudinal friction between the work-piece and the guide roll, when the speeds are as set up in the formula, and since the guide roll travels faster than the work-piece in the longitudinal direction, it now assists the work-piece through the mill instead of retarding it as was the case in all constructions heretofore. A speed of the guide roll in excess 80 of the formula given herein will of course 85 result in a further assistance of the piece through the mill. As any speed of the guide roll above the speed of the longitudinal travel of the billet will help in the forward movement of the billet as above stated, 90 then under the conditions of pressure exerted on the billet by the guide roll and the excess speed of the guide roll over the longitudinal travel of the billet, the power used in driving the guide roll expends it- 95 self in heat on the surface of the billet. By speeding up the guide roll even in excess of the formula given, where all matters of friction both against its transverse and longitudinal movement are satisfied, the 100 temperature may be brought to such a point as to bring about a welding heat on the surface of the work-piece over the extent of its reduction, and the circumferential travel bringing the heated parts in working 105 position under the reducing rolls at the welding temperature will definitely close these cracks.

In the preferred practice the guide roll will be positively driven and may be given 110 any desired speed regardless of the circumferential movement of the reducing rolls which affect the rotation and the rate of feed of the work-piece, such rate of feed being dependent on the angle between the 115 planes of rotation of the reducing rolls and the axis of the work-piece.

It is characteristic of the mill shown and described herein that the guide disc or roll can be made of any diameter greater than 120 the diameter of the reducing rolls provided that the transverse curvature of the working faces of the reducing rolls and the circle representing the path of movement of the base of the operating face of the guide roll 125 or disc have the same radii, and as the area of contact of the guide roll with the work-piece is small and as all other portions of the surfaces of the guide roll form heat radiating surfaces the guide roll can be made 130

of such diameter as to prevent any material heating of said guide roll when operating the mill.

When employing a guide disc or roll, with its axis of rotation at right angles to the direction of longitudinal movement of the work-piece, its strength to resist the pressure of the work-piece thereon will be proportional to the diameter of the supporting shaft. As the latter is arranged entirely to one side, i. e., above or below the rolls, it can be made of any desired diameter. As the guide disc or roll can be made of a thickness less than the diameter of the work-piece to be pierced, then very small work-pieces can be operated on in the improved mill.

When the reducing rolls are made of the same diameter and have the same peripheral speed, the vertical resultant of the lateral pressures of the two rolls on the work-piece as well as the amount of displacement which takes place in piercing or other factors will be equal, but if the peripheral speed of one roll is increased, the resultant pressure of the guide roll will be affected. As for example, an increase in the peripheral speed of the right hand roll in Fig. 1 will supplement the action of the vertical component of the pressures of said rolls to prevent the billet from moving upward and hence the billet may be fed on a line nearer the horizontal plane *c*. It will be understood that the increase in peripheral speed may be attained by increasing the speed of one of two rolls of the same diameter or by making one of the rolls of a greater diameter than the other and rotating the rolls at the same speed.

It will be observed that the tendency to shift the position of the work-piece by an increase in the peripheral rate of one of the rolls, will operate in the direction of rotation of such roll; as for example, an increase in the peripheral speed of the right hand roll in Fig. 1 would tend to move the work-piece down supplementing the vertical component of the lateral pressures on the work-piece and the weight of the work-piece and mandrel. If however, the peripheral speed of the left hand roll be increased, the effect of such increase will be to counteract to a greater or less degree dependent on the increase in peripheral speed, the combined action of the vertical component and the weight of the work-piece and mandrel, thereby decreasing the pressure of the work-piece on the guide roll. As the action of increasing the peripheral speed in a direction away from the supporting or guide roll would tend to shift the work-piece from between the rolls, great care should be exercised in using such a construction.

It is preferred in the practice of the invention claimed herein to feed the work-

piece between the reducing rolls so that its axis will be below a horizontal plane *c* and coincident with the intersection of planes *a* and *b* coincident respectively with the axes of the reducing rolls for the reason that in such case the weight of the work-piece and mandrel will operate to prevent the work-piece from being forced laterally through the narrowest space between the rolls and hence it is possible to so space the rolls for a given diameter of work-piece that the axis of the billet when being fed through the rolls will be closely adjacent to the plane *c*, thereby increasing the reducing efficiency of the rolls. As for example, under the present practice it has been found expedient to so feed the work-piece that its axis will be for a four-inch diameter work-piece about one and a quarter inches above the plane *c* so that the lifting effect of the vertical component of the pressures of the rolls on the work-piece will be largely in excess of the weight of the work-piece and mandrel. But by arranging the line of feed that the axis of the work-piece will be below the plane *c*, the weight of the work-piece and mandrel and the vertical component of the pressures of the rolls operate together to prevent the upward movement of the work-piece from between the rolls, the work-piece may be so fed between the rolls that its axis is not more than three quarters of an inch below the plane *c*.

I claim herein as my invention:

1. In a piercing mill the combination of reducing rolls adapted to act on the work-piece in a helical direction, and a guiding member having its axis of rotation in a plane at an angle to the axis of the work-piece being acted on by the reducing rolls, the portion of the guiding member in contact with the work-piece moving in the direction of the longitudinal movement of the work-piece.

2. In a piercing mill the combination of reducing rolls adapted to act on the work-piece in a helical direction, and a rotating guiding member adapted to bear on the portion of the work-piece having a diameter less than the diameter of the solid and pierced portions of the work-piece and having its axis of rotation at an angle to the direction of movement of the work-piece.

3. In a piercing mill the combination of reducing members and guiding member adapted to bear on the portion of the work-piece having a diameter less than the diameters of the solid and pierced portions of the work-piece, the portion of the guiding member bearing on the work-piece moving in a direction parallel with the axis of the work-piece.

4. In a piercing mill the combination of reducing members arranged in operative relation one to the other and having the surfaces operative on the work-piece, trans-

- versely curved, and a rotating guiding member adapted to support the work-piece in position to be operated on by the reducing members, the radius of the guiding member 5 being substantially equal to the radii of the transversely curved surfaces of the reducing rolls.
5. In a piercing mill the combination of reducing rolls adapted to act on the work-piece in a helical direction, and having curved operative faces and a guiding member having its axis of rotation in a plane at an angle to the line of feed of the work-piece to be pierced and adapted to bear on the portion of the work-piece being acted on by the reducing rolls, the radius of the guiding member being substantially equal to the radii of the curved surfaces of the reducing rolls.
- 10 6. In a piercing mill the combination of reducing rolls adapted to act on the work-piece in a helical direction, a guiding member having its axis of rotation in a plane at an angle to the axis of the work-piece and adapted to bear on the portion of the work-piece being acted on by the reducing rolls, and means for rotating the guiding member so that the surface in contact with the work-piece will move in the direction of longitudinal movement of the work-piece.
- 15 7. In a piercing mill the combination of reducing rolls adapted to act on the work-piece in a helical direction, a guiding member having its axis of rotation in a plane at an angle to the axis of the work-piece and adapted to bear on the portion of the work-piece being acted on by the reducing rolls, said guiding member being so arranged relative to the reducing rolls that its bearing on the work-piece will be below a horizontal plane coincident with the intersection of planes coincident with the axes of the reducing rolls, and the portion bearing on the work-piece will move in a direction of the longitudinal movement of the work-piece.
- 20 8. In a piercing mill the combination of reducing rolls having transversely curved reducing surfaces and a rotating guiding member, the radii of the transverse curvature of the reducing rolls and the guiding member being 50 substantially equal.
9. In a piercing mill the combination of reducing members and a guiding member having its peripheral surface moving in the direction of the work-piece being operated on, the radius of such surface being substantially equal to the radii of the surfaces of the reducing rolls and arranged to so support the work-piece being reduced that its center line will lie in a plane outside of but parallel 55 with a horizontal plane coincident with the point of intersection of planes coincident with the axes of the reducing rolls.
10. In a piercing mill, the combination of reducing members having their axes in 60 planes at an angle one to the other, and a guiding member so arranged that its point of contact with the work-piece will move in the direction of the longitudinal movement of the work-piece and having a rate of 65 rotation relative to that of the work-piece that the peripheral speed of the guiding member is approximately that of the circumferential speed of the work-piece divided by the sine of the angle of the helix of feed of 70 the work-piece.
11. In a piercing mill the combination of reducing members and a guiding member having its peripheral surface moving in a direction of the work-piece being acted on, 75 the radius of such surface being substantially equal to the radii of the surfaces of the reducing rolls and arranged to so support the work-piece being reduced that its center line will lie in a plane outside of but 80 parallel with the line of intersection of the planes coincident with the axes of the reducing rolls and the narrowest portion of the pass between the said reducing rolls.

In testimony whereof, I have hereunto set 85 my hand.

SAMUEL E. DIESCHER.
